City, Mo., a corporation

Application May 3, 1937, Serial No. 140,465

9 Claims. (Cl. 250—33)

This invention relates to radio systems, and particularly direction finding radio systems used in connection with airplanes and the like, and the primary object is to provide a specially constructed loop antenna for such aforesaid systems.

One of the important aims of this invention is the provision of an unique, rotatable loop for direction finding radio systems that is relatively inexpensive to manufacture, easy to assemble, and rugged in character when in use.

A yet further object of the instant invention is to provide a loop antenna of the aforesaid type, having as a part thereof, means whereby the inductance coil may be looped within the tubular, ring-shaped casing without encountering the heretofore troublesome problems which presented themselves during the manufacture of such equipment.

The specific embodiment of the broader concepts of this invention will be detailed during the course of the following specification, referring to the accompanying drawing, wherein:

Figure 1 is a side elevation of a loop antenna made in accordance with this invention, mounted as in use and diagrammatically associated with other parts of the radio system.

Fig. 2 is an enlarged, central, sectional view through the loop antenna per se.

Fig. 3 is an edge elevation of the same, with the outer element of a two-part supporting fixture removed.

Fig. 4 is a cross sectional view through the loop antenna, taken on line IV—IV of Fig. 2, and,

Fig. 5 is a similar sectional view, taken along line V—V of Fig. 2.

It has been found that a loop antenna constructed generally as illustrated herewith serves both the purpose of eliminating rain static and providing a direction and position finding device.

The loop antenna itself, broadly indicated by the numeral 8, is mounted beneath the fuselage 10 of the airplane in such manner as to permit its being rotated by the pilot from a place in the pilot's compartment and through the medium of a position indicator 12 that is equipped with a manually operable crank 14. Position indicator 12 is operably joined to rotating mechanism 16 through the medium of a torque control cable 18. A bracket 20, rigidly joined to some of the longitudinal stringers 22 of fuselage 10, carries rotating mechanism 16. The conventional radio receiver 24 is joined to rotating mechanism 16 by insulated conductors 26, and upon manipulation of crank 14, loop 8 and pointer 29 will be simultaneously actuated.

The manner of employing all of the aforementioned parts of the radio system diagrammatically illustrated is well known to those skilled in the art, and since the specific manner of constructing loop 8 forms the important part of this invention, reference may be had to Figs. 2 to 5 for an understanding of one illustrated embodiment.

A tubular ring-shaped casing 28 is initially a straight length of metal pipe, preferably aluminum, which is formed in any suitable manner so as to bring the ends 30 of the pipe into close proximity so that a tubular spacer 32 of insulating material may be positioned therebetween to break the continuity of the otherwise all metallic housing for the hereinafter mentioned inductance coil.

An opening 34 is provided through the wall of casing 28 for the passage of connections 36 which extend to radio receiver 24. After ring-shaped casing 28 has been formed, a resilient, preferably flat band 38 is threaded therethrough and its ends joined together by a link 40 of insulating material. This band 38 has a width less than the diameter of casing 28 so that its edges bear upon the inner face of casing 28, as shown in Fig. 4. After band 38 has been placed within casing 28, ends 30 are moved close together so as to diminish the diameter of casing 28, whereby band 38 may be rotated within the casing and about its axis. The looseness of fit between band 38 and casing 28 is maintained during the assembling operation, and thereafter ends 30 of band 38 are moved apart to receive spacer 32 and to increase the frictional relation between the edges of band 38 and the inner surface of casing 28. Thus band 38 is secured against relative displacement when the loop is in use. Obviously, spacer 32 must be first made of two or more sections so as to permit its being placed after band 38 has been made as just set down.

As band 38 is somewhat loosely and rotatably housed within casing 28, the antenna inductance coil is wound thereon. This inductance coil is made of insulated wire 42 and is carried by a series of blocks 44 that are on band 38. These blocks 44 are sectional so as to provide openings 46 for the reception of wire 42. In the preferred embodiment, sections 48 are formed as illustrated in Figs. 4 and 5, and the openings are notches created inwardly from one edge of each section 48. U-shaped clips 50 extend through perforations 52 provided in band 38 and radially outwardly extending legs of clips 50 pass through holes formed in each section 48 adjacent each end respectively thereof.

Sections 48 are progressively moved to posi-

tion as wire 42 is looped around and over the sections already in place, and when the desired amount of wire 42 has been fed into casing 28 by rotating band 38 and all of the blocks 44 carried thereby, the ends 54 of clips 50 are headed so as to hold sections 48 in place. Fig. 2 of the drawing teaches that there is a series of blocks 44 arranged in spaced relation around band 38. The ends of wire 42 form the connections 36 and through the construction just recited, no splicing of wire 42 occurs. The desired number of turns of wire 42 may be introduced into casing 28 upon blocks 44, and after the inductance coil is thus completed, spacer 32 is inserted and the two-part fixture placed around casing 28 over opening 34. This two-part fixture comprises a plate 56 and a co-operating neck element 58, the bore whereof is in communication with opening 34 and the interior of casing 28. Thus loop 8 may be 10 rotatably mounted on the rotating mechanism 16 and connections 36 joined to conductors leading from radio receiver 24.

Having thus described the invention, what is claimed as new and desired to be secured by Letters Patent is:

1. A loop antenna for direction finding radio systems comprising a looped housing having a unitary tubular, ring-shaped casing of electrical conductive material and a tubular spacer of insulating material breaking the continuity of the casing; an inductance coil within said housing; an annular band rotatably contained within the casing; and a series of blocks on the band, said inductance coil being carried by the said blocks.

2. A loop antenna for direction finding radio systems comprising a looped housing having a unitary tubular, ring-shaped casing of electrical conductive material and a tubular spacer of insulating material breaking the continuity of the casing; an inductance coil within said housing; an annular band rotatably contained within the housing; and a series of blocks on the band carrying said inductance coil, said blocks each being provided with spaced-apart openings therethrough for the reception of strands of the inductance coil.

3. A loop antenna for direction finding radio systems comprising a looped housing having a unitary tubular, ring-shaped casing of electrical conductive material and a tubular spacer of insulating material breaking the continuity of the casing; an inductance coil within said housing; an annular band rotatably contained within the housing; and a series of blocks on the band carrying said inductance coil, each of said blocks comprising a plurality of sections, the strands of the inductance coil being divided and disposed between the sections of said blocks.

4. A loop antenna for direction finding radio systems comprising a looped housing having a unitary tubular, ring-shaped casing of electrical conductive material and a tubular spacer of insulating material breaking the continuity of the casing; an inductance coil within said housing; an annular band rotatably contained within the housing; and a series of spaced-apart blocks on the band carrying said inductance coil, said annular band having a width less than the cross

sectional diameter of the said casing whereby to cause the annular edges of said band to engage the inner annular face of the casing.

5. A loop antenna for direction finding radio systems comprising a looped housing having a unitary tubular, ring-shaped casing of electrical conductive material and a tubular spacer of insulating material breaking the continuity of the casing; an inductance coil within said housing; an annular band rotatably contained within the housing; a series of sectional blocks on the band carrying said inductance coil; and clips securing together the sections of the blocks and the blocks to said band.

6. A loop antenna for direction finding radio systems comprising a looped housing having a unitary tubular, ring-shaped casing of electrical conductive material and a tubular spacer of insulating material breaking the continuity of the casing; an inductance coil within said housing; an annular band rotatably contained within the housing; a series of sectional blocks on the band carrying said inductance coil; and clips securing together the sections of the blocks and the blocks to said band, said inductance coil having parts thereof between the several sections of the series of blocks.

7. In an antenna of the character described having a tubular housing in the form of a loop; a continuous annular band, flat in transverse cross section, disposed within the housing with the edges thereof in line contact with the inner face of the housing; a plurality of sectional blocks mounted on one side of the band and extending radially outwardly from the band; an inductance coil comprising a continuous conductor looped upon the sections of said blocks with part of the loop between said sections; and common means for attaching together the sections of said blocks and the band.

8. In an antenna of the character described having a tubular housing in the form of a loop; a continuous annular band, flat in transverse cross section, slidably disposed within the housing with the edges thereof in line contact with the inner face of the housing; a plurality of sectional insulating blocks mounted on one side of the band and extending outwardly from the latter; and an inductance coil comprising a continuous conductor looped upon the sections of said blocks with part of the loop between said sections.

9. In an antenna of the character described having a tubular housing in the form of a loop; a continuous annular band, flat in transverse cross section, slidably disposed within the housing with the edges thereof in line contact with the inner face of the housing; a plurality of sectional insulating blocks mounted on one side of the band and extending outwardly from the latter; and an inductance coil comprising a continuous conductor looped upon the sections of said blocks with part of the loop between said sections, the width of said band being appreciably less than the inside diameter of the tubular housing, said sectional blocks being on the outer-most side of said band.

HOWARD K. MORGAN.
